US00D579117S

(12) **United States Design Patent**
Weiss et al.

(10) **Patent No.:** US D579,117 S
(45) **Date of Patent:** ** Oct. 21, 2008

(54) **CONTAINER FOR CLEANING MEDICAL INSTRUMENTS**

(75) Inventors: **Horst Chr. Weiss**, Muehlheim (DE); **Stefan Rehbein**, Immendingen-Hattingen (DE); **Peter Eisenkolb**, Tuttlingen (DE)

(73) Assignee: **Karl Storz GmbH & Co. KG** (DE)

(**) Term: **14 Years**

(21) Appl. No.: **29/254,534**

(22) Filed: **Feb. 24, 2006**

(30) **Foreign Application Priority Data**

Feb. 17, 2006 (EM) 000481460

(51) **LOC (8) Cl.** **24-01**

(52) **U.S. Cl.** **D24/217**

(58) **Field of Classification Search** D24/216-230; 422/292, 295, 297, 300, 301, 302; 206/370, 206/564; D32/55; D7/409, 704
